[57] CLAIM

The ornamental design for a lever tool handle, as shown and described.

DESCRIPTION

FIG. 1 is a front side perspective view of a lever tool handle showing my new design;

FIG. 2 is a rear elevational view of the lever handle of FIG. 1;

FIG. 3 is a left side elevational view of the lever handle of FIG. 1, the right side elevational view being identical, but in mirror image;

FIG. 4 is a front elevational view of the lever handle of FIG. 1;

FIG. 5 is a front elevational sectional view of the lever handle of FIG. 1, taken along section lines 5—5 in FIG. 3;

FIG. 6 is a bottom plan view of the lever handle of FIG. 1, taken along view lines 6—6 of FIG. 3;

FIG. 7 is a top plan sectional view of the lever handle of FIG. 1, taken along section lines 7—7 in FIG. 5;

FIG. 8 is a top plan sectional view of the lever handle of FIG. 1, taken along section lines 8—8 in FIG. 5; and,

FIG. 9 is a top plan view of the lever handle of FIG. 1. The broken line portions of the drawing are for illustrative purposes only and form no part of the claimed design.
